DRAPERY CRANE

John N. Graber, Madison, Wis.

Application October 6, 1941, Serial No. 413,809

2 Claims. (Cl. 248—265)

This invention appertains to means for supporting draperies on window frames, and more particularly to a novel adjustable drapery crane.

In all drapery cranes with which I am familiar, the drapery rod or bar is pivotally mounted at one end on the window frame bracket, and the bar lies in close relation with the window frame. With frames of this type, it is difficult to use draperies over Venetian blinds and glass curtains, and as the rod or bar is supported only at one end, the weight of the drapery tilts the rod or bar on its pivot, which prevents the drapery from hanging properly, and this presents an unsightly appearance.

It is, therefore, one of the primary objects of my invention to provide a drapery crane embodying a supporting fixture and a drapery rod or bar connected thereto in a novel manner, whereby the rod or bar can be moved in and out toward and away from the window in parallel relation to the window frame, whereby the draperies can be effectively supported different distances from the window frame for clearing Venetian blinds, glass curtains, etc.

A further salient object of my invention is to provide means for firmly supporting the drapery rod or bar intermediate its ends, whereby the tilting of the rod or bar under the weight of the drapery is prevented.

A further important object of my invention is to provide novel means for supporting the drapery rod or bar, whereby the rod or bar can be raised and lowered or slid longitudinally, so that the draperies can be hung to the best advantage under varying conditions.

A still further important object of my invention is to provide means whereby the draperies can be moved back and forth toward and away from the windows in parallel relation thereto, so that the right side of the draperies will always be exposed to view during the opening and closing of the windows.

With these and other objects in view, the invention consists in the novel construction, arrangement, and formation of parts, as will be hereinafter more specifically described, claimed, and illustrated in the accompanying drawing, in which drawing:

Figure 1 is a front elevational view of my novel crane, showing the same applied to a window.

Figure 2 is a horizontal sectional view through the window, taken on the line 2—2 of Figure 1, looking in the direction of the arrows, the crane being shown in top plan.

Figure 3 is a view similar to Figure 2, but show-

ing the drapery rod or bar in an adjusted position in spaced relation to the window frame for clearing a curtain and curtain rod.

Figure 4 is a detail sectional view taken on the line 4—4 of Figure 3, looking in the direction of the arrows.

Figure 5 is a view similar to Figures 2 and 3, but showing the supporting fixture connected with one side face of a window frame.

Referring to the drawing in detail, wherein similar reference characters designate corresponding parts throughout the several views, the letter C generally indicates my novel drapery crane, and W a window with which the same can be associated.

The crane C is of such a character as to permit the same to be associated with windows of various characters, and my crane includes a supporting fixture 10. This supporting fixture 10 can be in the nature of an angle bracket and includes a face plate 11 and a right-angularly extending arm 12. The face plate 11 can be secured to the preferred part of the window frame by suitable screws 13 or other fastening elements.

In connection with the supporting fixture 10, I utilize a bracket 14 for adjustably supporting the drapery rod or bar 15. The bracket 14 is also of an angle shape and includes a depending extending leg portion 16 and an inwardly extending right angular leg 17. The leg 17 of the bracket 14 is connected to the leg 12 of the supporting fixture 10 by means of links 18. The inner ends of the links 18 are connected for swinging movement to the fixture 10 by means of a pivot pin 19, and the outer ends of the links 18 are connected to the bracket 14 by means of a pivot pin 20. Hence, the links can swing on the supporting fixture 10, and the bracket 14 can be swung on the links.

The drapery rod or bar 15 can be of any desired length and is held on the depending leg 16 by means of an adjustable U-shaped bracket 21. The ends of the U-shaped bracket or clamping strap 21 have outwardly extending ears 22 formed thereon. These ears carry adjustable bolts 23, which extend through a vertical slot 24 formed in said depending leg 16. Obviously, by loosening the bolts 23, the U-shaped strap 21 and the drapery rod or bar 15 can be raised and lowered to suit various conditions, and by raising and lowering the rod or bar, the length of the draperies can be adjusted within certain limits. The rod or bar 15 can be readily slid back and forth within the U-shaped strap 21 to permit the draperies to be adjusted relative to the window frame and to allow different effects to be had.

Obviously, the rod or bar 15 receives the sliding eyes or hooks carried by the draperies, and as the arm itself is adjustable in a vertical plane, the necessity for a deep hem on the upper edge of the drapery is eliminated. The ends of the rod or bar 15 can be provided with struck-in ears 25 to act as stops for the eyes or hooks of the draperies, so as to prevent the accidental displacement of the eyes or hooks off the arm.

With my improved drapery crane, the arm 15 can be moved back and forth toward and away from the window frame in parallel relation thereto, and, thus, the rod or bar 15 can be effectively held different distances from the window frame. By this arrangement, the crane can clear Venetian blinds, curtains, curtain rods, and the like.

In Figure 2, the rod or bar 15 is shown in relatively close proximity to the window frame. In Figure 3, the rod or bar 15 is moved away from the window for effectively clearing a curtain rod 26 and a glass curtain 27. In Figures 1 to 4, inclusive, I have shown the supporting fixture 10 secured to the outer face of the window frame. In Figure 5, I have shown the fixture secured to the inner face of the window frame. Thus, the drapery crane is of a universal character and will fit mullions, as well as heads of casings for decorating a pair of windows. As the links 18 are supported from the upper end of the supporting fixture, the supporting fixture can be readily placed in back of Venetian blinds, curtains, and the like.

As the rod or bar 15 can be moved back and forth relative to the window, the proper side of the drapery will always be exposed to view when

opening or closing windows. In cases where it is desired to swing French windows wide open, the drapery rods or bars 15 can be swung back out of the way, as suggested in dotted lines in Figure 2.

Great stress is laid on the manner in which the rod or bar 15 is supported intermediate its ends by the clamping strap 21, in that the rod or bar is effectively held against tilting. Obviously, as parts of the drapery are carried by the rod or bar on each side of the bracket 14, the weight of the drapery is balanced on said rod or bar.

Various changes in details may be made, which do not depart from the spirit and scope of my claims, and what I claim as new is:

1. A drapery crane comprising, a supporting fixture adapted to be secured to a window frame, a drapery bar, a drapery bar bracket receiving said bar, a link pivotally connecting the bracket to the supporting fixture, said bar being adjustable vertically and horizontally on said bracket.

2. A drapery crane comprising, a supporting fixture adapted to be secured to a window frame, including an outwardly extending leg, a drapery bar, a drapery bar bracket including a depending vertically extending leg and an inwardly directed right angularly extending leg, a link pivotally connected to the leg of the fixture and to the inwardly extending leg of the bracket, and a clamp slidably mounted on the depending leg of the bracket in a vertical plane, said clamp slidably receiving the bar for movement transversely of the depending leg.

JOHN N. GRABER.
